UNITED STATES PATENT OFFICE

2,457,613

COMBINATION BEVEL

William Thomas, Keddie, Calif.

Application February 9, 1945, Serial No. 577,003

1 Claim. (Cl. 33—73)

1
This application is a continuation in part of my co-pending application Serial No. 465,341, filed November 12, 1942.

The object of the present invention is to provide a novel peep sight adapted to coact with the tongue of a combination bevel and in which the peep sight is provided with vertical and horizontal spirit levels.

The more specific objects and advantages of invention will become apparent from a consideration of the following description taken in connection with the accompanying drawings and illustrating an operative embodiment thereof.

In the drawing—

Figure 1 is a view in elevation showing the improved combination bevel.

Figure 2 is an edge view of the bevel looking from the left of Figure 1, with the tongue folded and with the accessories removed.

Figure 3 is a vertical sectional view taken on the line 3—3 of Figure 1.

Figure 4 is a vertical sectional view taken on the line 4—4 of Figure 1.

Figure 5 is a horizontal sectional view taken on the line 5—5 of Figure 1.

Figure 6 is a horizontal sectional view taken on the line 6—6 of Figure 1.

Figure 7 is an elevation of one of the plates of the stock.

Figure 8 is an end elevational view of the peep sight.

Figure 9 is a detailed elevation of the pivoted end of the body and tongue showing the bi-sector arm in position thereon and

Figure 10 is a fragmentary detail of the opposite side of the pivoted tongue showing how both sides thereof form a protractor.

Referring specifically to the drawings wherein like reference characters designate their like or similar parts throughout the different views, a stock is employed at 10. This stock or body is composed of a pair of plates 11 and 12 secured together in slightly spaced relation by means of rivets or the like 13 passing therethrough at one end and through spaced element 14 located between such plates. The side edges of the plates 11 and 12 are straight and parallel. Those of the respective plates register with each other as shown. Plate 11 along its opposite longitudinal edges preferably has integral outwardly extending flanges 15, while the plate 12 has similar flanges at 16.

On the outer surface of the plate 12 are provided scales as at 17, 18, 19, 20, 21, 22, representing respectively, sines, rises, degrees, secants,

hypotenuses, and inches. On the outer face 1 may provide scales also to represent for instance cosines, versed sines, etc. At the same time, it is to be understood that the particular arrangement of the location of the different scales may be varied and such scales placed at any feasible location or locations on the stock or body.

Coacting with the stock or body end is a blade or tongue 23 having an enlarged end 24 secured between the free ends of the plates 11 and 12 and pivotally mounted on a screw 25 passing through the plate at portion 24, having a head 26 and a nut 27 threaded on the bolt or screw and adapted to bind against the plate 11. The nut 27 will bind the parts together or hold them with sufficient friction to maintain the tongue in different adjusted positions or at different angles, while it may be loosened to enable the tongue to swing on the pivot afforded by bolt 25, to a folded position between the plates 11 and 12 as suggested by the dotted line in Figure 1.

Enlargement 24 has an arcuate edge so that degree indications may be delineated thereon and 28 and 28a on opposite sides of the tongue to form a protractor on both sides thereof.

Said tongue 23 it will be noted has parallel straight edges along which scales are provided as at 29, 30 to designate degrees and the length of arcs of predetermined radii. Any other arrangement of scales may be resorted to with respect to the tongue.

In connection with the tongue I provide a novel accessory in the form of a peep sight generally designated at 31. This sight is in the form of an elongated tube whose wall is opaque, and which tube is closed at the viewing end with the exception of a small central opening 32 while at the other end a reticule or crossed wires 33 are provided. Integral with or rigid on the tube 31 are clasp fingers 34 adapted frictionally to grip opposite sides of the tongue 23, since they are resilient, and one of which fingers has an inwardly extending lug or rib 35 detachably engaged in a groove 36. It is clear that the peep sight is detachably engaged in this manner with the tongue.

Horizontal spirit levels 47 and 48 are mounted on the opposite sides of the peep sight 31 and a third horizontal spirit level 49 is mounted on top of the peep sight. Vertical spirit levels 50 and 51 are also mounted on opposite sides of the peep sight.

Reverting to the stock 10, at specifically the plate 11, a central longitudinal slot 37 is provided. Detachably slidably in the slot 37 are T-shaped

heads or supports 38, 39 and 40 respectively, for a plumb level 41, an indicator 42 and a horizontal level 43. It will be noted that the heads 38, 39 and 40 are of the same width as the slot 37 to enable insertion or removal there-through, but that they are of a length so as to overlap and frictionally engage plates 11 and 12 when turned out of alignment with the slot 37. Such heads 38, 39 and 40 will be held by frictional pressure or clamp action between plates 11 and 12 when the nut 27 is tight. The pressure will be released upon loosening nut 27 to enable more rapid manipulation of the levels 41 and 43 and indicator 42.

As another accessory, I may employ a bisector arm 44 suitably calibrated if desired as at 45 to provide a linear measure, and one of whose straight longitudinal edges as at 46 intersects the axis of the bolt 25. This bisector arm is of relatively thin material and it has an opening at a point intermediate of its ends through which bolt 25 may pass, enabling detachable application of the bisector arm on the bolt between plate 11 and the nut 27, the latter being operable to clamp the bisector arm at a desired angle or position. The arm 44 may be utilized with the stock 10 as a secondary bevel, employing the edge 46 of the shorter end of the arm 44 as an index line for the protractor graduations 28, for positioning the arm 44 at any desired angle to the stock 10.

The bevel or tool described may be used in laying out plates, sheets, structural steel, buildings, etc., and for auxiliary uses such as laying out claims for prospectors, temporary surveys, finding altitudes and the like. The calibrations on the stock are so arranged that when the angle is found on the protractor, all that is necessary is to read off the chord, ordinate, arc, sines, versed sines, cosines, tangents, secants, rises, and hypotenuses opposite the degree marked on the tongue. The arrangement enables the obtaining of the length of hypotenuses, rises, arcs, chords, and ordinates as in my prior Patent No. 2,292,094. When the device is used with the peep sight 31 attached it will be realized that the stock or body 10 is disposed vertically and the tongue arranged at any desired angle, with the engineer or artisan sighting through the opening 32 in combination with the reticule or crossed wires at 33.

One of the numerous uses of the instrument is in the obtaining of the hypotenuse and rise of a large triangle, such as formed by an inclined guy wire, a stack and a base line, between the anchored base end of the guy line and the base of the stack. The peep sight can be employed to sight along the base line and by utilizing the spirit level 41, the stock 10 can be maintained perpendicular or with the level 43 can be maintained horizontally. By adjusting the blade, the sight 31 can be aligned with the base line, thus aligning the blade therewith so that the incline or decline of the base line can be read on the

protractor. By utilizing the levels on the body, said part can be disposed in a horizontal or vertical position and the peep sight and blade can then be aligned on the guy line so that the angular disposition of the guy line to the horizontal or vertical can be read from the protractor and by addition or subtraction of this reading with the reading obtained on the base line, the angle formed by the base line can be obtained. By measuring the length of the base line, it is possible to ascertain the hypotenuse or length of the guy line and rise or height of the stack to the point where the guy line connects therewith, by reading the hypotenuse and rise for a corresponding angle having a one foot base on the scales and by multiplying by the number of feet that the base line measures.

Obviously, the levels may be either single or double and the slots for the levels may be on one side or both sides. The pointer may go through one or both sides of the device. The openings may be of any shape, such as round or square or rectangular, may be made such as in combination bevels to accommodate telescope clips.

Various changes may be resorted to provided they fall within the spirit and scope of the invention.

Having thus described the invention, what I claim is:

An instrument of the class described comprising a stock, a tongue pivotally connected thereto and coacting therewith to form a bevel including a protractor, a peep sight carried by the tongue, a spirit level carried by the peep sight, said tongue having a longitudinal groove in one side thereof, disposed parallel to its longitudinal edges and opening outwardly of its free end, and said peep sight having a bracket comprising spaced, substantially parallel arms disposed perpendicular to its axis for engaging opposite sides of the tongue, one of said arms having an inturned free end for close fitting engagement with the groove for detachably mounting the peep sight on the tongue and in parallel relationship thereto.

WILLIAM THOMAS.
